UNITED STATES PATENT OFFICE

CHARLES HOTZE, OF ST. LOUIS, MISSOURI

GOLF BAG

Application filed December 30, 1929. Serial No. 417,315.

This invention relates to an improvement in golf bags and pertains more particularly to an improvement in the mouth ring of the bag for providing an improved manner of cooperation with the golf clubs while being carried in the bag.

Another object of the invention is in providing a golf bag at its mouth or golf club receiving end with improved means for eliminating valleying or bunching of the clubs so that ease of access to the clubs may be had.

A further object of the invention is in providing a golf bag with an improved mouth ring.

15 Other and further objects will appear in the specification and be specifically pointed out in the appended claims, reference being had to the accompanying drawing, exemplifying the invention, and in which:—

20 Figure 1 is a side elevation of a golf bag showing this improvement applied to the bag.

Figure 2 is an enlarged fragmentary vertical section taken through the upper portion 25 of the golf bag.

Figure 3 is a plan view of the mouth of the bag.

Figure 4 is a perspective view of the mouth ring used in the bag.

30 In the use of the present type of golf bags which are carried in an approximate position of inclination as shown in Fig. 1 by the strap 2 being engaged over the shoulder of a golfer or caddy, it is found that the circular mouth 35 ring permits the golf clubs to bunch one upon the other on the lower inclined side of the bag. This is occasioned by the clubs gravitating to the low side of the mouth ring and thus bunching one upon another and requiring

40 that the golfer or caddy spread the bunched clubs for selecting the next desired club to be used. This improvement in golf bags and particularly the mouth ring is therefore adapted to prevent the bunching or valleying 45 of the golf clubs at the mouth ring of the bag.

Referring to the accompanying drawing, 3 designates the golf bag having the bag wall 4, the base 5 and at the upper end of the bag 50 is the mouth 6.

55 The mouth 6 of the bag is reinforced by an

outer disposed collar 7 and an inner disposed collar 8, the upper end of the bag wall 4 being secured between said collars and disposed above said collars is a mouth ring 9, said mouth ring being secured in position by 55 an overlapping leather layer 10 which is inserted between the collars 7 and 8 in a desired manner. The mouth ring 9 is provided on one side with a straightened portion 11 and opposite thereto is an eyelet 12, said straightened portion being disposed on a plane lower or downward of the circular portions 13 of the mouth ring 9 and leading from the straightened portion 11 to each circular portion 13 is a downwardly inclined 60 portion 14 forming side portions to the straightened portion 11.

The leather layer or covering 10 for securing the mouth ring 9 in position covers all of the ring 9 with the exception of the eyelet 70 12, said eyelet being for the securing of the carrying strap 2 thereto at its upper end, the lower end of the strap being secured to the golf bag in the usual manner.

As the carrying strap eyelet 12 is secured 75 to the mouth ring diametrically opposite to the straightened portion 11 of the mouth ring, in the proper carrying of the bag in the approximate position shown in Fig. 1, obviously the golf clubs will incline against 80 the lower side 15 of the bag and consequently the striking ends of the golf clubs will rest against the straightened portion 11 of the mouth ring 9, and as the straightened portion 11 is of some length, the golf clubs 85 will wedge against each other in a somewhat straightened row thus preventing the piling or stacking of the clubs one upon another. This straightened manner of carrying the golf clubs in leaning positions against the 90 straightened portion 11 of the mouth ring will provide for easy selection and grasping of a desired golf club to be next used by the golfer.

The inclined portions 14 provide side members for the golf clubs when reposing against the straightened portion 11, said inclined portions tending to prevent the clubs from climbing the circular portions 13.

95 In the use of the present type of golf bags 100

which is circular in shape at its mouth, the bag upon being inclined in the carrying position causes the golf clubs to stack or bunch upon one another on the lower side of the bag because of the curvature thereof provided by the circular mouth. Obviously, with applicant's improved mouth ring having the straightened portion for cooperation with the inclining golf clubs, the clubs therefore will not pile as in the use of the present day circular shaped mouth ring.

If desired the mouth ring 9 can be made without the eyelet 12 and the carrying strap 2 can be secured to the ring 9 in opposite disposition to the straight portion 11 by a leather loop or the like.

While the mouth ring 9 is shown as being made from rod iron material, it is obvious that the ring can be made of any material such as by casting a relatively deep ring or collar having a flattened or straightened portion and while but one showing of the invention is disclosed, it is not my intention to limit its scope to that particular embodiment or otherwise than by the terms of the appended claims.

What I claim is:—

1. A mouth ring for a golf bag having a straightened portion disposed on a plane lower than the remaining portion of the ring, straight downwardly inclined portions joining the ends of said straightened portion with the remaining portion of the ring, and strap securing means in the form of an eyelet formed on the ring opposite to said straightened portion.

2. A mouth ring for a golf bag having a straightened portion and a straight downwardly inclined portion joining each end of said straightened portion with the remaining portion of the mouth ring.

3. A golf bag having a body wall and a mouth ring secured to the upper end of said wall having a curved portion and a straightened portion disposed on a plane lower than the remaining portion of the ring, and a straight downwardly inclined portion joining each end of said straightened portion with the curved portion of said mouth ring.

4. A golf bag having a body wall and a mouth ring having a lower disposed straightened portion secured to the upper end of said wall, said mouth ring having a straight downwardly inclined portion joining each end of said straightened portion to the other portion of the mouth ring, carrying strap secured to said ring in opposite disposition to said straightened portion thereof, said straightened portion being for cooperation with the golf clubs contained in the bag when the bag is borne in an inclined position by said strap.

CHARLES HOTZE.
